UNITED STATES PATENT OFFICE

JAMES H. RAND, JR., OF TONAWANDA, AND LOUIS C. BROECKER, OF BUFFALO, NEW YORK, ASSIGNORS, BY MESNE ASSIGNMENTS, TO REMINGTON RAND INC., OF NEW YORK, N. Y., A CORPORATION OF DELAWARE

INDEX OR RECORD DEVICE

Application filed February 2, 1924. Serial No. 690,284.

This invention relates to improvements in index trays or devices adapted to support index cards, card holders or other record bearing matter. More particularly the invention relates to devices of this sort which are formed of sheet metal, and are adapted to be slidably arranged one above another on partitions or other supports in an enclosing cabinet or case.

Trays or supports of this sort have heretofore been provided, having a back or bottom part on which the record-bearing cards are adapted to rest, and which engages and rests on the cabinet partitions or other supports, side walls extending upwardly from said bottom part with their upper edges in a plane adjacent to, or in contact with, the partition above, said side walls being arranged adjacent to or substantially engaging the side members or walls of the cabinet to guide the tray or slide in its movements into and out of the cabinet.

The cards or card holders are sometimes provided with flaps or tongues whereby an edge of one card or card holder may be inserted beneath the flap or tongue of an adjacent card or card holder to maintain them in overlapping, nested arrangement with the free edges of the cards projecting one beyond the other. The cards are further provided with lateral lugs or parts and the side walls of the trays are often provided with spaced, depending side flanges adapted to engage lateral lugs on the cards to retain the cards in their intended overlapping arrangement, lying substantially flat on the back or bottom part of the tray while the side flanges of the tray permit sliding movements of the cards in the tray and prevent their transverse displacement thereon.

Trays of the sort mentioned have further been provided with hinged or pivoted cover plates formed of thin flat sheets of metal or other material, one of which is usually arranged at an end of a tray and is adapted to lie on and protect the upper exposed face of the first or uppermost card or holder of the card series. The cover plate is thereby positioned substantially parallel with and lies adjacent to the cabinet partition immediately

above the tray on which the cover plate is secured.

In trays of this type in which the lower surface of the bottom or back part and the outer surfaces of the side walls contact substantially throughout the whole area of these surfaces with the cabinet partitions supporting the trays and the side members or walls respectively of the cabinet, a relatively great amount of friction and wear on the parts results. At the same time the sides and bottoms of the trays are usually formed with sharp 90° angles corresponding to the angles formed by the sides of the cabinet and the partitions. This has resulted in the sharp bottom side edges of the tray fitting closely or nesting in the angles of the partitions and sides of the cabinet and in some cases in their being liable to stick or freeze therein. When the trays and cabinets are provided with an enameled or other finish, as is customary, this finish is marred or broken, making the trays and cabinets very unsightly. The relatively great amount of friction requires the expenditure of an unnecessary amount of energy in inserting and withdrawing the trays, when it is remembered that these trays or slides are handled many times each day. Further, the somewhat rough or sharp edges of the depending card-engaging flanges of the tray rub on the side lugs of the cards and wear them to a harmful degree, due to the moving of the cards or holders relatively thereto, as well as preventing free and easy sliding movements of the cards, due to friction caused by the roughened edges referred to.

Also the cards or holders, after use, may buckle or bulge sufficiently to press the cover plate against the under surface of the adjacent cabinet partition and cause it to drag and wear thereon in the use of the tray, with the result that friction is present to an undesirable extent and the cover plate also becomes marred and unsightly.

The objects of the present invention are to provide card trays or slides, practically all portions of which are spaced from the parts of the cabinet in which they are inserted and in which the parts which do contact with the cabinet parts are of different form or angu-

larity from the parts with which they contact; also to provide a tray having rounded projecting portions adapted to bear against the cabinet partitions and side members or walls and form guiding and supporting means for the tray which will maintain the lower surface of the bottom part and the side wall surfaces of the tray out of contact with the cabinet parts, thereby reducing friction and 5 wear to a minimum; also to construct the depending card-engaging side flanges of the tray so that their edges will bear on the card lugs with the minimum of wear and friction and so that the edges of the body portions of 10 the cards will be held out of contact with the side surfaces of the flanges, whereby the life of the cards or card holders will be prolonged; also to provide a tray or slide having the bottom supporting part, side walls and depending 15 card-engaging flanges all formed of a one-piece sheet metal stamping, thereby simplifying the production and reducing the cost of production, while still maintaining a strong, rigid structure of minimum weight; 20 also to construct an improved cover plate of sheet metal or like material having parts adapted to maintain the major part of the surface of the cover plate out of contact with the adjacent cabinet partition or part, thereby 25 reducing friction and wear on the cover plate and preserving its original finished appearance; also to improve and simplify the construction of card index trays or slides in the other respects hereinafter set forth and 30 35 claimed.

In the accompanying drawings:

Fig. 1 is a plan view of a tray or slide and cover plate constructed in accordance with a preferred embodiment of the invention.

40 Fig. 2 is a side elevation thereof partly in section.

Fig. 3 is an enlarged, transverse, sectional elevation of the tray and cover plate, showing it in position on a supporting partition of a 45 cabinet, a part only of a cabinet being shown in section.

Fig. 4 is a fragmentary longitudinal section of the tray and cabinet on line 4—4, Fig. 3.

50 Fig. 5 is a fragmentary perspective view of a portion of a cabinet, showing the front portion of a tray supported therein, together with a sectional perspective of a portion of another tray.

55 The card tray or support preferably includes a bottom or back portion A, side walls B having spaced, overhanging flanges C adapted to engage tongues or portions D on the cards or holders E, which project beneath 60 the flanges, whereby the cards or holders are maintained in sliding engagement in the tray. The tray also includes a front wall F having apertures for the display of designating labels or the like, a handle or pull G, a rear wall H, and a removable back stop I

against which one end of the series of cards is adapted to abut to limit the longitudinal movements of the cards in one direction on the tray. The tray or slide, as thus far described, is of usual form adapting it to be used in a cabinet such as the cabinet K shown, said cabinet having partitions or the like L, or other supporting means, between which the trays may slide and on which they are supported. The cabinet also has side walls or members M between which the trays slide and are guided in their movements in and out of the cabinet. Any cabinet embodying these general features may be used.

According to the invention, the trays are so constructed that the major portions thereof are maintained spaced from the parts of the cabinet when the trays are inserted therein and the principal bearing parts which do contact with parts of the cabinet are of different shape, form or angularity from the parts of the cabinet on which they move. In the preferred embodiment of the invention shown in the drawings, the bottom portion A of the tray, side walls B and flanges C are formed integrally from a single sheet of metal, and means are provided whereby the outer surfaces of these bottom and side wall portions are maintained out of contact with the cabinet parts, said means constituting 90 bearings which are adapted to engage the tray supports and move thereon with the least possible friction. These means are also adapted to form guides for the tray in its movements into and out of the cabinet. For 95 use with a cabinet such as illustrated, wherein the sides of the cabinet and the partitions meet at substantially right angles, the means for this purpose preferably comprise a longitudinal offset bead or rounded rib 10 at each 100 side of the tray, formed as by stamping or striking out the corners at the juncture of the bottom A and side walls B. The two beads 10 are directed outwardly and downwardly in opposite directions and are adapted to engage in or lie substantially close to the 105 corners or angles 11 formed by the partitions L with the side walls M of the cabinet and thus support and guide the tray in its movements into and out of the cabinet with its 110 bottom and side faces out of contact therewith. The opposite side walls B and spaced card-engaging flanges C of the tray are preferably connected by longitudinal, rounded 115 connecting portions 12, which are arranged so as to lie in a plane adjacent the partition or part L of the cabinet immediately above the tray, so that if the tray, in its movements in the cabinet, should engage this partition or part, it will do so with the minimum 120 of friction due to the limited contacting areas, as the curved part 12 presents very little surface to rub against the cabinet parts. By the construction described, the tray is provided 125 with practical guiding means enabling it to 130

be easily and smoothly moved into and out of the cabinet while the original finish on the tray is preserved from being marred or injured. The beads 10 and rounded upper connecting portions 12 also strengthen and reinforce the body of the tray, while the one-piece construction appreciably reduces the weight thereof. In the preferred form of the invention, the card-engaging flanges C are provided with means for reducing to a minimum the friction and wear between the flanges C and the card lugs D so that a smooth surface is presented to the card lugs, said means also being adapted to maintain the side edges of the cards or card holders E out of contact with the side faces of the flanges C. These means, as shown in the drawings, see Figs. 3-5, are preferably in the form of an integral, rounded bead or rolled edge portion 13 formed at the lower or free edge of each of the flanges C, said edges 13 having rounded, longitudinal card lug engaging portions 13^a extending along their lower extremities and rounded inwardly-extended and longitudinally-arranged side portions 13^b adapted to limit lateral movements of the cards E by engaging their side edges, thereby also preventing these edges from contacting with the side faces of the flanges C. The cards are therefore subjected to much less wear than in cases where straight side flanges are provided, and consequently the life of the cards is prolonged. The free edges of the metal forming the flanges C are turned upwardly into the space between the flanges C and the side walls B of the tray so that no part of the cards, holders, or other record devices can come into contact therewith.

The tray shown in the drawings is provided with a cover plate 15 preferably formed of a thin, flat sheet of metal and which is adapted to be pivotally connected to the rear part of the tray, as by providing apertures in the flanges C into which lateral pivot parts 16 on the cover plate are adapted to extend, or in any other suitable manner. The body portion of the plate, as usual, extends from side to side of the tray between the flanges C, and its length is such that it extends over and covers the record matter on the exposed upper face of the uppermost card or holder E, leaving only the free edge of the card or holder exposed, see Fig. 4. It will be noted that the adjacent underlying cards together normally tend to maintain the cover plate 15 substantially parallel with the bottom A of the tray and in a plane close to the under side of the partition L above it, so that normally it may move with the tray beneath said partition without contacting therewith. However, in the use of the tray, the cards are manipulated to an extent such that they may become slightly buckled or flexed, or an additional number of cards may be added to the card holders and forming a thicker layer of

cards beneath the cover plate, thus causing the cover plate to be lifted so that its outer or free portion is forced into engagement with the partition L above it, with resultant friction and wear, and consequent marring of the finish on the cover plate 15. This invention provides means for obviating this objection, and in the preferred form shown in the drawings, these means comprise a plurality of upwardly extending, rounded portions or ribs 17 which may be formed by integral bosses, or in any other suitable manner. The ribs 17, as shown in Figs. 3 and 4, are adapted to afford the minimum of contact between the cover plate 15 and the adjacent partition L, so that substantially the whole area of the cover plate is maintained out of contact with the partition under the conditions stated above, thus reducing friction between these parts and resulting in greater ease of operation and a minimum of rubbing or marring of the cover plate or other parts. The ribs 17 also give increased strength and rigidity to the cover plate with no increase in weight. When the trays are used in a cabinet, as stated above, they are usually provided with a hinged tail piece, such as shown at 20, adapting the trays to be pulled out sufficiently to expose their contents, without being entirely removed from the cabinet. For this purpose the tail piece 20 is usually formed with depending hooks or parts 21, adapted to engage a part at the front of the cabinet, as for instance, the upturned hooked or flanged edge 22 of the partition L on which the tray slides, so preventing the tray from being withdrawn from the cabinet.

In the cabinet shown in the drawings, the flanged edges 22 terminate short of the junction of the partitions L with the cabinet side walls M, thus leaving spaces 23 for the free passage of the offset, rounded ribs 10 of the trays, while the lower edges of the tray front walls F are cut away so as to be flush with the lower faces of the bottoms A of the trays, thereby permitting the interfitting of the tray fronts with the front edges of the partitions L.

The trays and cabinets, however, may be formed without the tail pieces 20 and flanges 22 respectively and they form no part of the present invention.

We claim as our invention:

1. In a tray or slide formed of sheet-metal and adapted to be slidably moved in and out of a cabinet having spaced tray-supporting parts between which the trays are adapted to slide, the top portions of a tray extending adjacent the supporting parts for the tray next above, parts on said tray for maintaining record devices thereon, and a hinged cover member on said tray adapted to extend over and protect the record matter on one of said record devices, and relatively small, upwardly extending parts on said cover mem-

- ber adapted to engage the tray-supporting parts for the next upwardly adjacent tray to maintain the body portion of said cover member out of contact with said tray-supporting parts, whereby friction between said cover and adjacent tray-supporting parts is reduced during sliding movements of said tray and wear on the body portion of the cover member is prevented.
10. 2. In a tray or slide formed of sheet metal and adapted to be slidably moved into and out of a cabinet, a bottom on said tray adapted to support a plurality of hingedly connected record members and having an integral side wall formed along each longitudinal edge of said bottom, an inwardly extending integral top section formed along the top edge of each side wall, a downwardly extending flange formed on each top section, and a longitudinal, rounded bead formed on the bottom edge of each flange, said beads having a portion extending inwardly between said flanges adapted to engage the edges of said record members during the swinging movement thereof about their hinge members, said beads and bottom being also adapted to detachably confine said hinge members therebetween.
30. 3. In a tray or slide formed of sheet metal and adapted to be slidably moved into and out of a cabinet, a bottom on said tray adapted to support a plurality of hingedly connected record members, integral, tubular beads having means for spacing said beads from said bottom and adapted to cooperate with said bottom to detachably support hinge portions of said record members therebetween, said tubular beads also adapted to engage the edges of said record members during the swinging thereof, and a sheet-metal cover member hingedly mounted on said tray adapted to extend over and protect the record matter on one of said record members, said cover member having embossed portions adapted to space said cover member apart from said cabinet during the movement of said tray.
40. 4. A drawer for an index or file, having a bottom generally flat and horizontally disposed, tubular portions formed at the sides of said bottom having portions extending below the bottom, portions extending upwardly from said tubular portions to form the side walls, said tubular portions projecting beyond said side walls, and inwardly and downwardly extending portions at the upper edges of the side wall portions terminating in spaced relation above the bottom.
50. 5. A drawer for an index or file, having a bottom generally flat and horizontally disposed, tubular portions formed at the sides of said bottom having portions extending below the bottom, portions extending upwardly from said tubular portions to form the side walls, said tubular portions projecting be-

yond said side walls, and inwardly and downwardly extending portions terminating in beaded edges having the lower portions spaced from said bottom.
